UNITED STATES PATENT OFFICE.

CARLTON R. RADCLIFFE, OF NEW YORK, N. Y., ASSIGNOR TO INTERNATIONAL PATENT CORPORATION, OF JERSEY CITY, NEW JERSEY, A CORPORATION OF NEW JERSEY.

INTERNAL-COMBUSTION ENGINE.

No. 895,194.

Specification of Letters Patent.

Patented Aug. 4, 1908.

Application filed August 3, 1907. Serial No. 386,952.

To all whom it may concern:

Be it known that I, CARLTON R. RADCLIFFE, a citizen of the United States, and a resident of the city of New York, in the county of New York and State of New York, have invented certain new and useful Improvements in Internal-Combustion Engines, of which the following is a specification.

- 10 The invention relates to improvements in internal combustion engines, and particularly to those engines termed "two cycle engines", and in which there are three or more cylinders. The invention provides a construction, in which the common practice, of utilizing the crank case as the receiving chamber for the gas to be introduced into the cylinders, is eliminated. In engines of this general character, as hereinbefore in use, 15 it has been customary to allow the combustible mixture to enter the cylinders from a chamber where the mixture is under a certain degree of pressure. When therefore the inlet port is opened and the combustible mixture enters the working cylinders, it is obvious, that the pressure of the combustible mixture suddenly drops down to the atmospheric pressure, since the working chamber is in communication with the open air by 20 means of its outlet. It will be observed, therefore, that the work used to obtain the pressure, hereinbefore mentioned, in the receiving chamber is lost. Another serious defect of these engines consists in the fact that, 25 since the combustible mixture enters the cylinder under pressure, the larger part of the charge enters the cylinder, when the inlet port opens. The products of combustion will, therefore, mingle with the entering 30 fresh charge, whereby the quality of the latter will be impaired. A still further defect of the engines of the character specified and hereinbefore in use consists in the fact that the new charge never expels the products of 35 combustion from the clearance space.

It is now the object of the present invention to provide an internal combustion engine, in which the combustible charge is under atmospheric pressure or little above atmospheric pressure when the same enters the cylinders of the engine. The pressure being very low or there being atmospheric pressure in the space wherefrom the charge enters the cylinders, consequently the power used for compressing the charge, and lost

when this very low pressure drops down to the atmospheric pressure, is very slight. Since the pressure in the chamber, containing the combustible mixture, is very low or there being no pressure at all therein, a small part of the combustible mixture enters the working cylinder, when the inlet port is opened and the amount, entering the cylinder, gradually increases as the port gradually opens, therefore the products of combustion have more time to escape and will not be mixed with the entering new charge.

Means are provided, whereby the products of combustion are entirely expelled from the working cylinders, including also their clearance spaces. Means are also provided whereby in case of a "back-fire" the effect is not a retarding one as usual in the two cycle engines, and the cycle of the engine is not upset, when a back-fire occurs.

Broadly speaking, the invention consists of a plurality of cylinders of the so called "double diameter" type. The pistons working in the cylinders are also of the double diameter construction, their smaller part fitting the smaller portion of the cylinders and forms the working portion, while their larger parts fit the larger parts of the cylinders and by their movement to and fro alternately draw in the combustible mixture from the carbureter and transfer it to the working chambers of the pistons.

Adjacent to the cylinders is arranged a suitable chamber, hereinafter to be referred to as the "receiving chamber", for receiving the gas from the carbureter, and connected to the pump chamber of each cylinder, which connections are controlled by valves, one for each cylinder. These valves are provided in the said connections to prevent the mixture from being forced back into the carbureter. The pump chamber of each cylinder is on the other hand connected to a second chamber, which connection is again controlled by valves, one for each cylinder. This second chamber will hereinafter be referred to as the "distributing chamber".

In each working space of the cylinders is arranged an inlet- and an outlet-port, the inlet port making a communication between the distributing chamber and the working space of the cylinders, while the outlet ports lead into the open air. The construction of the inlets is such, that one or more of the working spaces of the cylinders are always

in communication with the distributing chamber. Since the distributing chamber is always through one or more working spaces of the cylinders and their corresponding outlets in communication with the open air, it will be seen, that atmospheric pressure or very little above atmospheric pressure exists in the distributing chamber.

The volume of the pump cylinders is in excess of the volume displaced by the working pistons, consequently the charge transferred by the pumping pistons will entirely fill the working chamber and also the clearance space of the same, expelling thus entirely the products of combustion from the working spaces and clearance spaces of the cylinders. Another effect of the peculiar construction of the inlets, herebefore mentioned, is that each pump piston supplies a given amount of the new charge to the working spaces, which are in communication at a given time with the distributing chamber. This fact will be hereinafter more fully described.

The distributing chamber is provided with a plurality of valves, opening toward the open air, and held in place by springs, which allow the valves to open when the pressure in the distributing chamber becomes too high, for instance when a back-fire occurs in one of the cylinders.

The invention is illustrated in the accompanying drawings, in which

Figure 1 is a vertical section of an engine taken on a plane through the center of one of the cylinders. Fig. 2 is a vertical section taken in a plane through the center of the cylinders and parallel to the shaft of the engine. Fig. 3 is a top view of the engine, and Fig. 4 a side elevation, partly in section, of the same. Figs. 5, 6 and 7 show diagrams of a three cylinder engine, while Figs. 8, 9, 10 and 11 are diagrams of a four cylinder engine.

In Figs. 1 to 4, inclusive, a three cylinder engine is shown. 1-1 indicates the supporting beams of the engine, to which the frame 2 of the latter may be secured in any suitable way, and having brackets 3 for the bearings of the crank-shaft 4. To the frame 2 are secured in a well known manner the combination working and pump cylinders 5, the working portion 6 whereof is of less diameter than the pump portion 7. The working portions of these cylinders are provided with gas inlet ports 8 and exhaust ports 9. Water-jackets 10 surround the working cylinders 5 for a purpose well known in the art. While in this particular form the engine is shown as "water cooled", the invention is not confined thereto. The pistons 11 of the engine are also combined working and pump pistons, their working and pump portions 12 and 13, respectively, fitting the corresponding portions 6 and 7 of the cylinders. The usual packing rings 14 may be supplied to

make an airtight fit with the surrounding cylinder walls. A deflector 11' is arranged on the top of the pistons 12 to facilitate the scavenging of the cylinders. 15 indicates the connecting rods, connecting the pistons to cranks, and 16 designates a fly-wheel secured to the crankshaft of the engine for a purpose well known in the art. Near to the cylinders is located a receiving chamber 17, receiving the combustible mixture from the carburetor (not shown in the drawings), through a pipe 18. The receiving chamber communicates with the pump chambers of the cylinders, which communications are controlled by valves 20, held under the tension of springs 21, and opening toward the pump chambers of the cylinders. When, therefore, the pistons move down to the end of their working strokes, a combustible mixture is drawn into the pump chambers, which is on the upward stroke of the pistons transferred from the pump chamber to a distributing chamber 22. It will be observed that the pump cylinders have practically no clearance spaces, therefore a high vacuum may be created in the same. The suction on the carburetor will be therefore very strong, which fact allows of a wide range for throttling. The distributing chamber is located above the said receiving chamber and communicates with each of the pump chambers of the cylinders and these communications are again controlled by valves 23, held under the tension of the springs 24. On the upward stroke of the pistons the combustible mixture will, first, be slightly compressed, until its pressure overcomes the tension of the springs 24, and since the valves 20 are closed by this pressure, the combustible mixture will then enter the distributing chamber. 25 indicates valves of the distributing chamber which open toward the open air, and are controlled by springs 26, adjusted so as to allow the opening of the valves, when the pressure in the distributing chamber becomes too high, as for instance, when a back-fire occurs. The object of the valves 25 is also to provide means, whereby an easy access may be had to the valves 20 and 23 and also to their controlling springs. 27 designates an igniter of suitable construction and for a well known purpose. The inlet ports are uncovered by the pistons 12 on their downward stroke and closed by the same on their upward stroke. The height of the inlet ports is such, that the same remain open during the travel of the pistons corresponding to an angular travel of their cranks of a slightly greater angle than the angle under which the cranks of the engine are disposed.

In Figs. 5 to 7 diagrams of a three cylinder engine are shown, illustrating the different positions of the cranks during a part of the revolution of the crankshaft. In this engine,

as well known, the cranks I, II and III are located in planes 120° apart. The height of the inlet ports corresponds to an angular travel of $120^\circ + 2f^\circ$, which angle is shown in the figures in dotted lines. As shown in Fig. 5 the piston of crank II has just opened the inlet, while the piston of the crank III is just about to close its corresponding inlet. Following now the rotation of the crank-shaft, it will be observed that the inlet port, controlled by the piston of crank II, is about to be closed, when the inlet port controlled by the piston of crank I is already opened (Fig. 7). Following now further the rotation of the crank-shaft, it will be easily seen that one of the inlets is always in communication with the distributing chamber or, in other words, the distributing chamber is always through one of the inlets and their corresponding exhaust ports in communication with the open air. Each of the pump pistons furnishes a predetermined quantity of combustible mixture to the working cylinders. It will be observed that the inlet of the cylinder II is opened at an angular distance of $120^\circ - f^\circ$ from the vertical and, as stated hereinbefore, remains open during an angular advance of the piston of crank II of $120^\circ + 2f^\circ$, and during this time the charge entering the cylinder II is pumped into the same by the pumping pistons of the cranks III, I and II. More particularly, when the inlet port opens during an angular advance of f° the charge is pumped into the cylinder by the pistons of crank I and crank III, thence during an angular advance of 60° by piston III, and thence during an angular advance of 60° by pistons of cranks II and III, and during an angular advance of f° only by piston of crank II.

In Figs. 8 to 11 diagrams of a four cylinder engine are shown, and it will be seen that in this case again more than one of the inlets will always be in communication with the distributing chamber. Otherwise the same relations will be true; of course, the angular distances, above mentioned, are not the same. In this particular case the height of the inlet corresponds to an angular distance of $90^\circ + 2f^\circ$. In case of a more than 4 cylinder engine again other angular distances will be given. Attention is called to the fact that the volume of the pump cylinders is in excess of the volume displaced by the corresponding working pistons of the cylinders, therefore the incoming charge will entirely expel the products of combustion. Exhaust ports 9 of the cylinders are about in the same plane as the inlet ports therein, but are uncovered on the down stroke of the pistons before the inlet ports are uncovered, so that the burned gases may escape. The outflow of the burned gases is aided in the usual way by the inflow of the new charge and by the deflector 11'.

In operation of the engine, the combustible charge is introduced on the down stroke of a piston through pipe 18 into the receiving chamber 17, and, since valve 20 opens, there being a vacuum in pump chambers 7— 70 to pump spaces 7. On the upward stroke of the pistons the combustible mixture of the pump chambers will be first slightly compressed, and, as the pressure overcomes the tension of the spring 24 of the valve 23, this 75 valve will be lifted and the charge will flow into the distributing chamber 22, and thence it will be introduced into a working cylinder. The piston within the combustion space compresses the charge, ignition takes place 80 and the piston is driven forward. The cycle of operation is then repeated.

What I claim is:

1. In an internal combustion engine, the combination with a plurality of working cylinders, of a plurality of pump cylinders, and a communicating passage from all of said pump cylinders to all of said working cylinders, said passage being always through one or more of said working cylinders in communication with the atmosphere. 85

2. In an internal combustion engine, the combination with a plurality of working cylinders, of a corresponding plurality of pump cylinders, and a communicating passage 95 from all of said pump cylinders to all of said working cylinders, said passage being always through one or more of said working cylinders in communication with the atmosphere.

3. In an internal combustion engine, the combination with a plurality of working cylinders, of a corresponding plurality of pump cylinders, an inlet and an exhaust in said working cylinders, a distributing chamber common to all of said working cylinders and adapted to be always through one or more of said cylinders in communication with the atmosphere, and a passage leading from each pump cylinder to said distributing chamber. 100

4. In an internal combustion engine, a plurality of cylinders, a pumping chamber in each, a combustion chamber in each, a piston separating the pumping chamber from the combustion chamber in each cylinder, and a communicating passage from all of said pumping chambers to all of said combustion chambers and being always through one or more of said combustion chambers in communication with the atmosphere. 110

5. In an internal combustion engine, a plurality of cylinders, a pumping chamber in each, a combustion chamber in each, a piston separating the pumping chamber from the combustion chamber in each cylinder, a gas receiving chamber common to all of said pumping chambers, a valved passage for each pumping chamber and leading from said gas receiving chamber to said pumping chamber, and a valve- and piston-controlled passage leading from all of said pumping 120 125 130

chambers to all of said combustion chambers and being at all times through one or more of said combustion chambers in communication with the atmosphere.

5. 6. In an internal combustion engine, the combination with a plurality of working cylinders having inlets, and outlets located in the same plane as said inlets but being of a greater height than said inlets, of a plurality 10 of pump cylinders, and valve - controlled means connecting said pump cylinders and said working cylinders and affording constant communication between some one of said pump cylinders and some one of said 15 working cylinders.

7. In an internal combustion engine, the combination with a plurality of working cylinders having inlets, and outlets located in the same plane as said inlets but being of a 20 greater height than said inlets, of a plurality of pump cylinders, and means connecting said pump cylinders and said working cylinders and affording communication at some 25 point in each cycle between some one of said pump cylinders and a plurality of said working cylinders.

8. In an internal combustion engine, the combination with a plurality of working cylinders having inlets, and outlets located in 30 the same plane as said inlets but being of a greater height than said inlets, of a plurality of pump cylinders, and means connecting said pump cylinders and said working cylinders and affording communication at some 35 point in each cycle between a plurality of said pump cylinders and some one of said working cylinders.

9. In an internal combustion engine, the combination with a plurality of working cylinders having inlets, and outlets located in the same plane as said inlets but being of a greater height than said inlets, of a plurality 40 of pump cylinders, and means connecting said pump cylinders and said working cylinders and affording communication at some 45 point in each cycle between a plurality of said pump cylinders and a plurality of said working cylinders.

10. In an internal combustion engine, the combination with a plurality of working cylinders, of a corresponding plurality of pump cylinders located coaxially with said working cylinders, and a communicating passage 50 from all of said pump cylinders to all of said working cylinders, said passage being at all times through one or more of said working cylinders in communication with the atmosphere.

11. In an internal combustion engine, the combination with a plurality of working cylinders, of a plurality of pump cylinders located coaxially with said working cylinders, an inlet and an exhaust in said working cylinders, a distributing chamber common to

all of said working cylinders and adapted 65 to be always through one or more of said working cylinders in communication with the atmosphere, and a passage leading from each of said pump cylinders to said distributing chamber.

12. In an internal combustion engine, the combination with a plurality of working cylinders having inlets, and outlets located in the same plane as said inlets but being of a greater height than said inlets, of a plurality 75 of pump cylinders located coaxially with said working cylinders, and valve controlled means connecting said pump cylinders and said working cylinders and affording constant communication between some one of 80 said pump cylinders and some one of said working cylinders.

13. In an internal combustion engine, the combination with a plurality of working cylinders having inlets, and outlets located in 85 the same plane as said inlets but being of a greater height than said inlets, of a plurality of pump cylinders located coaxially with said working cylinders, and means connecting said pump cylinders and said working cylinders and affording communication at some 90 point in each cycle between some one of said pump cylinders and a plurality of said working cylinders.

14. In an internal combustion engine, the combination with a plurality of working cylinders having inlets, and outlets located in the same plane as said inlets but being of a greater height than said inlets, of a plurality 95 of pump cylinders located coaxially with said working cylinders, and means connecting said pump cylinders and said working cylinders and affording communication at some point in each cycle between a plurality of said pump cylinders and some one of said working cylinders.

15. In an internal combustion engine, the combination with a plurality of working cylinders having inlets, and outlets located in the same plane as said inlets but being of a greater height than said inlets, of a plurality 110 of pump cylinders located coaxially with said working cylinders, and means connecting said pump cylinders and said working cylinders and affording communication at some 115 point in each cycle between a plurality of said pump cylinders and a plurality of said working cylinders.

16. In an internal combustion engine, the combination with a plurality of working cylinders having inlets, and outlets located in the same plane as said inlets but being of a greater height than said inlets, of a plurality 120 of pump cylinders, a gas receiving chamber common to all of said pump cylinders, a passage from said gas receiving chamber to each 125 of said pump cylinders, and a communication from all of said pump cylinders to all of

said working cylinders and being always through one or more of said working cylinders in communication with the atmosphere.

17. In an internal combustion engine, the combination with a plurality of working cylinders having inlets, and outlets located in the same plane as said inlets but being of a greater height than said inlets, of a plurality of pump cylinders, a gas receiving chamber common to all of said pump cylinders, a passage from said gas receiving chamber to each of said pump cylinders, a distributing chamber common to all of said working cylinders and being always through one or more of said working cylinders in communication with the atmosphere, and a passage from each pump cylinder to said distributing chamber.

18. In an internal combustion engine, a plurality of cylinders, a pumping chamber in each, a combustion chamber in each, a piston separating the pumping chamber from the combustion chamber in each cylinder, a gas receiving chamber common to all the pumping chambers, a passage from said gas receiving chamber to each of said pumping chambers, and a valved passage from all of said pumping chambers to all of said combustion chambers and being at all times through one or more combustion chambers in communication with the atmosphere.

19. In an internal combustion engine, the combination of a plurality of cylinders, a pumping chamber in each, a combustion chamber in each, a piston separating the pumping chamber from the combustion chamber in each cylinder, a gas receiving chamber common to all the pumping chambers, a valved passage from the gas receiving chamber to each pumping chamber, a distributing chamber common to all of said combustion chambers, a valved passage from each of said pumping chambers to said distributing chamber, a piston controlled passage from said distributing chamber to each of said combustion chambers, and a valve in said distributing chamber and adapted to release any undue pressure from the combustion chambers.

20. In an internal combustion engine, a plurality of cylinders, each cylinder having two distinct and different internal diameters, a piston for each of said cylinders, each pis-

ton having two distinct and different diameters corresponding to the internal diameters of the respective cylinder, said cylinder forming a combustion chamber at the end of each piston, a pumping chamber around each piston, and a communicating passage from all of said pump cylinders to all of said working cylinders and being always through one or more of said combustion chambers in communication with the atmosphere.

21. In an internal combustion engine, the combination of a plurality of cylinders, a pumping chamber in each, a combustion chamber in each, a piston separating the pumping chamber from the combustion chamber in each cylinder, a gas receiving chamber common to all the pumping chambers, a valved passage leading from the gas receiving chamber to each pumping chamber, a distributing chamber common to all of said combustion chambers and being at all times through one or more of said combustion chambers in communication with the atmosphere, a valved passage from each pumping chamber to said distributing chamber, and a passage from said distributing chamber to each combustion chamber.

22. In an internal combustion engine, the combination of a plurality of cylinders, a pumping chamber in each, a combustion chamber in each, a piston separating the pumping chamber from the combustion chamber in each cylinder, a gas receiving chamber common to all the pumping chambers, a valved passage from the gas receiving chamber to each pumping chamber, a distributing chamber common to all of said combustion chambers and being at all times through one or more of the combustion chambers in communication with the atmosphere, a valved passage from each pumping chamber to said distributing chamber, and a piston controlled passage from said distributing chamber to each combustion chamber.

Signed at New York, in the county of New York and State of New York, this 31st day of July, A. D. 1907.

CARLTON R. RADCLIFFE.
